CONTINUOUS INTERLEAVED RECORD
ASSEMBLY

Joseph Loweth, New York, N. Y., assignor, by
mesne assignments, to J. Stuart Fleming, Ni-
agara Falls, N. Y.

Application May 21, 1930, Serial No. 454,225

1 Claim. (Cl. 282—12)

This invention relates to improvements in manifolding or record assemblies of the type employing long continuous record and transfer strips interleaved in transfer relation with each other so that inscriptions made upon the upper or original record strip will be transferred by the transfer strip or strips to the interleaved or copy record strips.

It is common to interleave blank forms with carbon sheets so that type impressions may appear on all of the several forms or blanks in the set at one writing, but such interleaving is troublesome, as well as the arrangement of the blanks in accurate registration, on ordinary type-writing machines.

Even with machines built for such specific purpose, separation of the fan forms from the carbons is not readily accomplished and crocking or smudging often occurs.

It is an object of the present invention to provide a novel series of integral blanks, two, three, four or more, interleaved with continuous strips of carbon paper, the blanks being accurately adjusted and held, together with the carbons, in a manner completely precluding relative slip.

A further feature is in the provision of a multiple leaved strip or assembly of the class mentioned and of an improved construction that can be used in any standard typewriting machine with entire facility and removed and replaced without danger of disarrangement.

Another aim is to produce a manifold series of blanks, separable from succeeding series, but held against individual separation by an improved construction and arrangement until after inspection and approval.

These several important objects are accomplished by the novel combination and arrangement of parts hereinafter described and illustrated in the accompanying drawing, forming a material part of this disclosure, and in which:

Fig. 1 is a perspective view of a series of blank and carbon sheets in strip formation of any desired length as arranged in accordance with the invention.

Fig. 2 is a plan view of two consecutive blanks arranged for manifolding, the uppermost blank being partially torn away.

Fig. 3 is a transverse sectional view, taken on line 3—3 of Fig. 2, and drawn to an enlarged scale.

As shown in the drawing, the manifold pile consists of four blank record strips or sheets 10a—10b—10c and 10d, all, or a portion, of which bear imprinted forms as indicated, but, which do

not affect the invention, other than the forms are arranged in exact registration.

Interleaved between the blanks are carbon strips or sheets 11a—11b and 11c, both the blanks and carbons being uniform in width and of continuous length.

These several sheets are firmly held by a row of stitches 12 adjacent one of their marginal edges and extending the entire length of the roll or fan-fold form in which they are supplied.

Adjacent the stitches is a row of perforations 13, the space therebeyond being occupied by the printed form.

The several series of blanks are bent or folded into a zigzag supply pack or assembly along transverse rows of perforations 14 which serve eventually to permit ready separation from the continuous interleaved manifolding assembly of a set of record and carbon leaves interleaved in transfer relation, after the typing has been done.

It is to be noted that the row of perforations 13 merge with or embody elongated slits or shear cuts 15 adjacent the cross perforations 14, thus enabling a small section 16 of the margin containing the stitches to be easily removed by an operator and in order to avoid soiling the fingers in separating the series, thumb notches 17 are cut in each of the carbon sheets or leaves and are longitudinally spaced along the assembly, preferably intermediate the opposite longitudinal edges of the carbon strips and at the upper edges of the respective carbon sheets or leaves. As shown, these openings or notches 17 may be positioned substantially centrally of the upper edges of the carbon sheets and contiguous to and merging with the respective weakened severance lines 14.

By virtue of this arrangement the edges of the carbon sheets at these openings 17 are inset from the overlying and underlying adjacent edges of the record sheets, so as to provide selective grip formations. When a set of leaves is severed from the assembly along the weakened severance lines 14 these openings 17 will be caused to open through the adjacent edges of the carbon leaves or sheets, thus completing the selective grip formations.

Thus it will be seen that after separation of the typed set of blanks, the uppermost sheet may be inspected and checked prior to grasping said blanks at the margin 16 and at the thumb notches 17 to tear off said margin containing the stitches 12 and freeing the blanks or inscribed form sheets, the carbons however being held attached to the marginal strip at the corner under the shear cuts 15 in the blanks. The carbons are

imperforate at 15. The inscribed record sheets may thus be quickly and easily severed from the longitudinal marginal binding along the respective severance lines 18 and at the same time stripped or separated from interleaved relation with the carbon sheet.

While certain preferred embodiments of this device have been shown and described, it will be understood that changes in the form, arrangements, proportions, sizes and details thereof may be made without departing from the scope of the invention as defined in the appended claim.

Having thus described my invention, what I claim as new and desire to secure by Letters Patent, is:

15. In a manifolding assembly, in combination, long continuous record and transfer strips interleaved in transfer relation and having longitudinally spaced transverse weakened severance lines 20 whereby the assembly may be divided into record units of interleaved record and transfer sheets, said record strips having longitudinally disposed weakened severance lines extending along one longitudinal assembly margin and transversely of

5 said transverse severance lines to each said record unit so as to form a longitudinally disposed detachable binding margin for each said record strip at each said record unit, said binding margins of the respective record strips being relatively superposed, said record and transfer strips being attached together at said binding margins at each said record unit, each said transfer sheet of each record unit having a grip opening spaced inwardly from each of the opposite longitudinal transfer strip edges and adjoining the respective transfer strip severance lines whereby the respective transfer sheets have edges inset from the adjacent record sheet edges so as to provide a selective grip formation spaced from the binding 10 margin at each said record unit, said longitudinal severance lines of the record strips having elongated cuts adjacent to the respective transverse weakened severance lines and said transfer strip being unweakened corresponding to said longitudinal weakened severance lines of the record strips. 15 20
